US00D572914S

(12) **United States Design Patent**
Overthun et al.

(10) **Patent No.:** **US D572,914 S**
(45) **Date of Patent:** **** Jul. 15, 2008**

(54) **CHAIR**

(75) Inventors: **Thomas Overthun**, San Francisco, CA (US); **Judy G. Davis**, Fort Worth, TX (US); **Kurtis K. Kemper**, Kennedale, TX (US)

1,157,351 A 10/1915 Weber
1,233,218 A 7/1917 Gent
1,336,062 A 4/1920 Arton
1,348,813 A 8/1920 Landine
1,350,360 A 8/1920 Crane

(73) Assignee: **Steelcase Inc.**, Grand Rapids, MI (US)

(**) Term: **14 Years**

(Continued)

(21) Appl. No.: **29/260,940**

FOREIGN PATENT DOCUMENTS

(22) Filed: **Jun. 5, 2006**

(57) **CLAIM**

The ornamental design for a chair, as shown and described.

DESCRIPTION

FIG. 1 is a perspective view of a chair, showing our new design;

FIG. 2 is a right-hand side elevational view;

FIG. 3 is a left-hand side elevational view;

FIG. 4 is a front elevational view;

FIG. 5 is a rear elevational view;

FIG. 6 is a top plan view; and,

FIG. 7 is a bottom plan view.

The dashed lines in the figures show the environment of the present design and are not part of the present design.

1 Claim, 7 Drawing Sheets
